UNITED STATES PATENT OFFICE.

ARTHUR FRANCIS BERRY, OF EALING, ENGLAND, ASSIGNOR TO GENERAL ELECTRIC COMPANY, A CORPORATION OF NEW YORK.

ELECTRIC HEAT-RADIATOR.

1,330,576.

Specification of Letters Patent. Patented Feb. 10, 1920.

Application filed December 13, 1915. Serial No. 66,453.

To all whom it may concern:

Be it known that I, ARTHUR FRANCIS BERRY, a subject of the King of Great Britain and Ireland, residing at Ealing, in the county of Middlesex, England, have invented Improvements in or Relating to Electric Heat-Radiators, of which the following is a specification.

This invention has reference to electric heat radiators of the kind in which heat is produced in a bare strip or wire of resistance metal or alloy carried by an insulating support and it has for its object to provide an electric heat radiator of this kind which, when in use, shall produce not only luminous and heat radiating effects but shall also produce, especially when seen from a distance, an effect resembling upwardly moving smoke and flame so that such radiator shall present an appearance resembling to some extent, that resulting from the combustion of fuel.

Another object of my invention is to provide a method of operating heat radiators whereby the same effect is produced.

In a heat radiator for this purpose constructed according to the present invention, the resistance metal or alloy is made in the form of a thin narrow strip, or wire of small diameter (hereinafter included in the term strip) and arranged to form one or more upwardly extending open-work screen-like structures of small mass over and around which, when rendered luminous by the passage of an electric current therethrough, air can readily flow in an upward direction and come in contact therewith and vary the temperature of the different parts of the resistance by cooling the same irregularly at different parts thereof and to different degrees, the part or parts with which the air first comes in contact being cooled to such an extent that it or they temporarily loses its or their luminosity, becoming to a greater or less extent and in a constantly varying manner, black in parts while other parts with which the air comes in contact, after it has become more or less heated, become dulled to a less and varying extent, this dulling action becoming less and less as the air rises. In this way an effect is produced resembling the varying shape and movement of smoke and flame. For the purpose of facilitating the production of

the effect described, the resistance screen or screens may be so disposed in front of a backing as to form one or more airways that will act as a draft passage or passages and facilitate the upward flow of air over the openwork resistance screen or screens. By this arrangement and owing to the varying refrangibility of the ascending air which becomes heated to varying degrees, the effect described is enhanced, a greater body and depth being apparently given to the smoke and flame effect. The backing may have a reflective front surface or surfaces which may be suitably adapted, in any known or suitable way, as by curving or corrugating it, or forming it with a number of facets, as for example by providing it with a number of comparatively small and short pyramidal projections, that light impinging thereon from the luminous screen or screens will be reflected back through the screen or screens practically in all directions through the air in and about the radiator.

Several screens or radiators of the kind described may be provided arranged in various ways, as for example side by side in a straight row, or in a curved row, or around a common center. Or one screen may be arranged in front of another or others inclined thereto or parallel thereto as seen in plan.

Electric heat radiators adapted to produce an effect such as described can be variously constructed.

In the accompanying illustrative drawings, Figure 1 shows in front elevation, Fig. 2 in horizontal section on the line A A of Fig. 1, and Fig. 3 in vertical section on the line B B of Fig. 1. one construction of heating apparatus embodying a number of electric heat radiators according to the invention. Fig. 4 is a similar view to Fig. 3 showing an alternative arrangement. Figs. 5, 6 and 7 are similar views to Figs. 1, 2 and 3 respectively showing a modified construction of heat radiator according to the invention. Figs. 8 and 9 show in side elevation and horizontal section respectively and to an enlarged scale part of the heat radiator shown in Figs. 5, 6 and 7.

In the example shown in Figs. 1, 2 and 3 each heat radiator comprises a length of resistance material in the form of a very thin

2
and narrow strip or ribbon *a*, wound backward and forward in a horizontal direction between the notched forward edges *b*¹ of two vertical strips *b* of non-conducting material, 5 such as sheet mica, so as to form a vertical openwork screen comprising as shown, a number of superposed straight horizontal strips spaced a short distance apart, say about an eighth of an inch, and arranged 10 with their flat sides more or less horizontal so that air can readily flow over and all around them for dulling them in varying places and to varying extents for producing the desired effect hereinbefore referred to. 15 The resistance screen is thus freely exposed to the air and is also exposed to the room or other space to be heated, so that the same is visible therefrom. The resistance strip or ribbon may have a width of about thirty 20 mils and a thickness of about three mils and be of such a length-and resistance that the electric current passed through it will render it a dull to bright red so that it can be readily cooled in parts by upwardly flowing 25 air currents. Each radiator should be of sufficient width and height to enable the desired smoke and flame effect to be produced. Good effects have been obtained with radiators of the kind shown having a 30 width of about two and a half to three inches and a height of from say eight to ten inches but the invention is not limited to these dimensions. The notched edges *b*¹ of the mica strips may be protected by small 35 U-shaped metal clamps *b*². The strips *b* of mica are secured to the opposite edge portions *c*¹ of a vertical backing *c* of concave shape in horizontal section and having preferably a more or less reflective front surface 40 to enhance and give greater reality to the smoke and flame effect hereinbefore referred to, the space *d* formed between the vertical resistance screen and the backing *c* serving to contain air as and for the purpose hereinbefore mentioned and through which air 45 may if desired be permitted to flow in contact with the rear side of the screen at the same time that air can flow over the front side thereof. The ends of the resistance 50 strip *a* may be connected to insulated terminals *a*³ carried by the backing *c* and adapted to be readily engaged with fixed terminals *a*⁴ at the back of the heating apparatus the terminals *a*³, *a*⁴ constituting respectively for example a plug and socket, so 55 that each radiator can be easily placed in position for use and removed. At the bottom of the heat radiating apparatus thus formed and extending in a forward direction therefrom, there may be provided means such as for example as a plate *e*, having a reflective upper surface. Above the top of the radiator may be means such as for example as a cover *f* of any desired shape, adapted, it 60 may be, to guide upwardly flowing heated 65

air away from the radiator and diffuse it through the room or apartment in which the radiator is placed.

Each openwork screen instead of being vertical as shown in Fig. 3 may be inclined 70 to the vertical as shown in Fig. 4.

The straight parallel strips of resistance material *a* constituting the openwork screen, instead of being arranged with their flat sides more or less horizontal as shown in 7 Figs. 1, 2 and 3, may be arranged with their flat sides vertical or nearly so and it may be one above the other in a single plane, or it may be in two or more planes one behind the other. Figs. 5, 6 and 7 show the straight 8 horizontal lengths of thin resistance strip *a* arranged flatwise in a single vertical plane. For the purpose of enabling adjacent straight lengths of flat resistance material to be thus arranged flatwise, such lengths 8 may, as shown to an enlarged scale in Figs. 8 and 9, be connected together by short integral connecting portions *a*² arranged in a plane parallel to that containing the adjacent straight lengths *a* and produced by 9 bending the length of resistance strip or ribbon flatwise around angularly shaped teeth arranged alternately at the opposite sides of a former or formers made of sheet material, as described in the specification of 9 my application for British Letters Patent No. 8829 of 1915. The openwork screen thus formed of thin strip resistance material as described, is held in position by oppositely arranged vertical strips *b* of sheet 1 insulating material, such as mica, that extends vertically between the overlapping portions of the horizontal lengths *a* and the intermediate connecting portions *a*² of resistance strip or ribbon, and is formed with 1 teeth *b*¹ having inclined edges engaging the inclined edge portions *a*² of the resistance strip material at the bends or folds therein. In other respects the arrangement shown in Figs. 5, 6 and 7 may, as shown, be similar 1 to that shown in Figs. 1, 2, and 3.

The resistance strip *a* may be waved, crimped or equivalently shaped along its length, or parts thereof.

A heat radiator or heat radiators constructed as and for the purpose hereinbefore described may, as shown in Figs. 1, 2 and 3, be mounted upon or within a frame or holder *m* of any suitable shape or design.

What I claim is:—

1. An electric heating device comprising a series of spaced resistance elements operating at visible incandescence, a support therefor provided with a flue back of said elements in free communication with the 1 spaces between the elements.

2. An electric heating device comprising a series of spaced resistance elements formed of a resistance material, mounted on a curved refractory base with an air space 1

between said material and base, operable at visible incandescence, a support therefor, provided with a flue back of said elements in free communication with the spaces between the elements.

3. An electric heat radiator comprising strip resistance material and a vertically extending support having straight denticulated marginal regions connected by a backing, the strip material being disposed in horizontal straight lengths from one marginal region to the other to form a plane open-work screen with a space between it and the backing constituting a draft passage for air, said screen being operable at

incandescence in view from the space to be heated and being of small mass whereby the temperatures of different parts of the screen are visibly variable in an irregular manner during operation.

4. An electric heat radiator comprising strip resistance material, a curved metal backing and separate marginal members of insulating material secured to the backing and between which the strip material is disposed.

Signed at London, England, this 24th day of November, 1915.

ARTHUR FRANCIS BERRY.
